UNITED STATES PATENT OFFICE

2,164,693

PLOW

Joseph Burton Berryhill, Combes, Tex.

Application January 25, 1937, Serial No. 122,262

1 Claim. (Cl. 74—538)

The present invention relates to new and useful improvements in plows of the sweep type and has for its primary object to provide, in a manner as hereinafter set forth, an implement of this character embodying a construction and arrangement which is such that the sweep may be conveniently adjusted to operate at any desired angle or inclination.

Another very important object of the invention is to provide a plow of the aforementioned character embodying novel means for releasably securing the sweep in adjusted position.

Other objects of the invention are to provide a plow of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a plow constructed in accordance with the present invention, the sweep being omitted.

Figure 2 is a view in top plan of the invention, one of the handles being broken away.

Figure 3 is a cross sectional view, taken substantially on the line 3—3 of Fig. 1.

Figure 4 is a perspective view of the standard.

Figure 5 is a detail view in perspective of the pawl.

Figure 6 is a perspective view of the runner and the rudder thereon.

Referring now to the drawings in detail, it will be seen that the embodiment of the invention which has been illustrated comprises a metallic beam 1 having means 2 secured on its forward end for connection with a suitable source of power. Secured at an intermediate point on the rear end of the beam 1 is a longitudinally extending runner 3 having fixed on its rear end portion a depending rudder 4. Forwardly of the rear end of the beam 1, the runner 3 extends upwardly as at 5, and terminates in a forwardly projecting end portion 6.

The reference numeral 7 designates handles of suitable material, preferably wood, which are secured to the rear portion of the beam 1 by metallic straps 8. Braces 9 extend from the beam 1 to the handles 7. Extending between the handles 7 is a brace 10. The reference numeral

11 designates a quadrant which is rigidly secured on the curved portion of the beam 1.

Mounted for swinging movement on the forward end portion 6 of the runner 3 is a standard which is designated generally by the reference numeral 12 and which is adapted to have mounted on its lower end portion the sweep (not shown). The standard 12 comprises comparatively long and short complementary bars 13 and 14, respectively, the lower end portions of which project forwardly at an angle. The bars 13 and 14 are pivotally mounted on opposite sides of the forward end portion 6 of the runner 3, as at 15. The bars 13 and 14 extend upwardly on the opposite sides of the beam 1 and the quadrant 11 and have their upper end portions secured together by a spacing block 16 having an opening 17 therein. The spacing block 16 has projecting therefrom threaded shanks 18 which extend through the bars 13 and 14 and which have threaded thereon securing nuts 19. Below the spacing block 16 and adjacent the quadrant 11, the bars 13 and 14 have formed therein transversely aligned slots 20.

The bar 13, it will be noted, extends above the upper end of the bar 14 and terminates in a right angularly projecting handle 21. Pivotally mounted on the upper portion of the bar 13, below the handle 21, is a lever 22. The reference numeral 23 designates a substantially T-shaped pawl the shank of which is slidably engaged in the opening 17 of the spacing block 16. The head of the substantially T-shaped pawl 23 is slidably in the slots 20 and engageable with the quadrant 11 for releasably securing the standard 12 in adjusted position. A coil spring 24 encircles the shank of the substantially T-shaped pawl 23 and has one end engaged with the spacing block 16 and its other end engaged with the head portion of the pawl for yieldingly urging said pawl toward the quadrant 11. A suitable rod or wire 25 connects the pawl 23 to the lever 22 for actuation thereby against the tension of the spring 24.

It is thought that the operation of the plow will be readily apparent from a consideration of the foregoing. To adjust the angle of the sweep the substantially T-shaped pawl 23 is disengaged from the quadrant 11 through the medium of the lever 22 after which the standard 12 may be conveniently swung to the desired position on its pivot 15. When the lever 22 is released the spring 24 immediately engages the pawl 23 with the quadrant 11 for securing the standard 12 in adjusted position. The construction and ar-

angement of the handle 21 and the lever 22 is such that the pawl 23 and the standard 12 may be conveniently operated with one hand with a minimum of effort.

5 It is believed that the many advantages of a plow constructed in accordance with the present invention will be readily understood and although a preferred embodiment of the implement is as illustrated and described, it is to be understood 10 that changes in the details of construction and in the combination and arrangement of parts may be resorted to which will fall within the scope of the invention as claimed.

What is claimed is:

15 A lever for plows comprising a pair of spaced, parallel pivotally mounted bars having opposed longitudinal slots therein, a spacing block mount-

ed between the bars adjacent the slots, said block having an opening therein, threaded shanks on said block projecting through the bars, securing nuts for said bars threaded on said shanks, a substantially T-shaped pawl between the bars slidably mounted in the opening in the block, the head portion of said pawl being operable in the slots, said pawl being engageable with a keeper for releasably securing the bars against swinging movement, a coil spring mounted on the pawl and having one end engaged with the block and its other end engaged with the head portion of said pawl for yieldingly urging same toward operative position, and means on one of the bars for retracting the pawl.
